H. STEINBACH.
COAL CHUTE.
APPLICATION FILED NOV. 5, 1919.

1,416,073.

Patented May 16, 1922.

Inventor,

Henry Steinbach,
By Thos. A. Lehman,

Attorney

UNITED STATES PATENT OFFICE.

HENRY STEINBACH, OF SCRANTON, PENNSYLVANIA, ASSIGNOR TO JOHN J. STEINBACH, OF SCRANTON, PENNSYLVANIA.

COAL CHUTE.

1,416,073.

Specification of Letters Patent. Patented May 16, 1922.

Application filed November 5, 1919. Serial No. 335,967.

To all whom it may concern:

Be it known that I, HENRY STEINBACH, a citizen of the United States of America, and resident of Scranton, in the county of 5 Lackawanna and State of Pennsylvania, have invented certain new and useful Improvements in Coal Chutes, of which the following is a specification.

This invention relates to chutes for coal 10 while being treated in coal breakers and the said invention has for its object the provision of novel means whereby coal in its travel from screens or rollers to the coal assorting pockets may be retarded so that it 15 will not gain undesirable velocity in its movement through the chutes.

As now made, these chutes are on an incline and the coal often gravitates with such speed as to impair and disintegrate the coal 20 when the lumps impact each other or the sides of the chutes when turning the angles or corners of said chutes. The coal thus impaired results in a great deal of waste and it is this that the inventor seeks to minimize.

An object of this invention is to provide novel means which may be attached to chutes now in use or which may be constructed and installed when the new chutes are built, the 30 said device having novel means for attaching the retarding device to said chutes so that the cost will not be large compared with the great value of the improvement.

With the foregoing and other objects in 35 view, the invention consists in the details of construction and in the arrangement and combination of parts to be hereinafter more fully set forth and claimed.

In describing the invention in detail, reference will be had to the accompanying 40 drawings forming part of this specification wherein like characters denote corresponding parts in the several views, and in which—

Figure 1 illustrates a view in perspective of a fragment of the chute with the invention applied thereto;

Figure 2 illustrates a longitudinal sectional view of a fragment of a chute; and

Figure 3 illustrates an end view thereof. In these drawings 5 denotes a chute and

6 the sectional linings or plates therein, having upstanding sides which are attached to the sides of the chute by fastenings 7 such as rivets or the like.

55 The coal retarding device comprises a plate 8 which is transversely corrugated as shown at 9, the undulations of the corrugations being high or low according to the type of coal being treated and the sizes which are 60 to pass down the chutes.

The lower end of the plate 8 is straight and forms a flange which may be secured to the inturned flanges 10 of the sides of the lining plates, and the undulated plate is secured to these flanged sides preferably by rivets 11, it being shown in the drawing that the concaved portions of the plates rest on the flanges of the sides so that these concaved portions may be secured to the flanges 65 to insure a strong and durable construction. In practice, it has been found unnecessary to have a number of rivets which equal the concavities of the plates; in fact it is sufficient under most conditions to secure the 70 plate at every alternate concaved portion, but that is a matter that is within the discretion of the purchaser or user and I do not 75 wish to be limited with respect to this feature.

80 The height of the corrugations would of course depend upon the pitch of the chute and the coal which would travel down the chute and that is also a matter within the discretion of the manufacturer or user.

85 This device should not be regarded as a separator but is a part of the distributing chute through which the coal is directed after it has been fully treated in the pickers and separators.

I claim—

In a coal retarding attachment for chutes, plates having corrugations extending transversely, side plates having inturned lower edges forming flanges to which the first 95 mentioned plates are secured, the said plates and side plates being adapted to be secured in a chute at different pitches for offering resistance to the passage of material down the chute, according to the pitch of the 100 chute.

HENRY STEINBACH.
